UNITED STATES PATENT OFFICE

ALFRED D. STOUT AND HUGH F. McNALLY, OF RICHLAND CENTER, WISCONSIN

GLOBE VALVE RESEATING TOOL

Application filed April 23, 1931. Serial No. 532,360.

This invention aims to provide novel means for grinding a valve seat, even though the tool may not be held exactly at right angles to the seat. A mechanic can make changes in the form shown, within the scope of the claim, and not depart from the spirit of the invention.

Figure 1 is an elevation, wherein the valve has been sectioned; Figure 2 is a bottom plan 10 of the grinder, with attendant parts in section; Figure 3 is a cross section of the grinder; Figure 4 is a plan of the guide, with a part of the shank in section; Figure 5 is an end view of the shank.

15 The numeral 1 marks a valve casing provided with a seat 2 having a hole 3.

The tool embodies a metal shank 4, the end 5 of which is shaped to fit in a bit stock, or other rotating tool, not shown.

20 The shank 4 carries a conical abutment 6, the lower end 7 of which is convexedly rounded, and below the convexed end, the shank has a polygonal (square) portion 8 connected to a cylindrical tip 9 which is

25 threaded at 10 to receive a nut 11 holding a guide 12 on the tip 9, the tip fitting somewhat loosely in the opening of the guide, and the opening of the guide being flared in opposite directions, as shown at 14. The guide 30 12 is circular, and fits in the hole 3 of the seat 2.

The numeral 15 marks a grinder, in the form of a circular disk, provided with a ribbed or roughened grinding surface 16, 35 adapted to cooperate with the upper surface of the seat 2. The grinder 15 has a square hole 17 receiving the squared portion 8 of the shank 4 loosely, the grinder having a concaved seat 18 above and about the hole 17, and a correspondingly shaped recess 19 below and above the hole. The convexed end 7 of the abutment 6 can rock in the seat 18.

The guide 12 is put in the hole 3 of the seat 2, the grinder 15 rests on the valve seat 45 2 and is pressed thereagainst by the abutment 6, and when the shank 4 is rotated, the grinder 15 will be rotated by the squared portion 8 of the shank, the upper surface of the seat 2 being smoothed off, as is required when the seat is pitted or worn.

The seat 2 will be surfaced properly even though the shank 4 is not held at right angles to the seat 2. This is so because the convexed end 7 of the abutment 6 can rock in the seat or recess 18, the squared portion 8 moving in the recess 19, and the tip 9 having the necessary tilting movement in the circular, flared recesses 14 of the guide 12.

What is claimed is:

A tool for grinding valve seats, comprising a shank having an abutment with a convexed lower end, the shank having a polygonal portion, below the abutment, and having a tip below the polygonal portion, a guide held loosely on the tip and provided with oppositely flared recesses, enabling the tip to swing laterally in the guide, and a grinder having a polygonal hole receiving the polygonal portion of the shank, the grinder having a lower, flared recess in which said polygonal portion can rock, and the grinder having an upper flared seat in which the convexed end of the abutment is received for rocking movement.

In testimony that we claim the foregoing 75 as our own, we have hereto affixed our signatures.

ALFRED D. STOUT.
HUGH F. McNALLY.
